MAGNETIC SEPARATOR

Ernest Grossenbacher, Fajardo, Puerto Rico

Application December 11, 1935; Serial No. 53,873

3 Claims. (Cl. 209—215)

The invention relates to magnetic separators designed primarily for removing stray pieces of iron, steel or other substances responsive to magnetism from masses of material, for instance in the treatment of the latter during manufacturing processes, and has for its object to provide a novel type of magnetic separator adapted to operate with a maximum of efficiency and to positively remove the stray pieces of iron, steel or other substances responsive to magnetic influence from the material and to hold the same in separated relation to said material for convenient disposal at periodic intervals. Other more specific objects will appear from the description hereinafter and the features of novelty will be pointed out in the claims.

In the accompanying drawings, which, without defining the limits of my invention illustrate an example thereof embodied in a cane crushing apparatus, Fig. 1 is a fragmentary vertical section of a cane crushing apparatus equipped with my novel magnetic separator; Fig. 2 is a section on the line 2—2 of Fig. 1 with portions of the apparatus omitted for purpose of clarity; Fig. 3 is a vertical view, partly in section, of the magnetic separator in a form designed specially for use in cane crushing apparatus; Fig. 4 is a plan view of the magnetic separator, partly in section, showing the disposition of the magnetic coils therein; Fig. 5 is a vertical section on the line 5—5 of Fig. 3; Fig. 6 is an enlarged detail view showing the magnetic separator and a section of the lower crusher roll of the cane crushing apparatus, and Fig. 7 is a detailed perspective view of the specially designed magnet cores which form an essential part of my invention.

For convenience of description the novel magnetic separator has been illustrated in combination with a cane crushing apparatus for which it is particularly adapted, it being understood however that the novel separator is equally well adapted for other apparatus and machines in which corresponding problems are developed and that accordingly the selected illustration is not to be construed as defining the limits of the invention.

Referring more particularly to Figs. 1 and 2 of the drawings which show parts of a conventional cane crushing apparatus, 10 represents the usual supporting frame on which the customary crushing rolls 11 and 12 are mounted in any well-known way for rotation in the direction of the arrows in Fig. 1. The rolls 11 and 12 in practice are relatively widely set and may be rotatably actuated by the usual gears 13 and preferably are each

provided with peripheral ribs or grooves 14 in the well-known way, it being understood that in the illustrated machine the mat of sugar cane is passed between said rolls 11 and 12 for the purpose of crushing the cane as is well-known. Below the crushing rolls 11 and 12 and at a distance therefrom is located the first of a series of mills each of which may, as shown, comprise a set of co-operating closely set rolls 15 between which the crushed cane is passed, said rolls 15 being journaled on the frame 10 and operated, for instance in the direction of the arrows in Fig. 1, in any conventional manner.

In its illustrated form the novel magnetic separator includes a scraper tip 19, preferably magnetized as hereinafter set forth and having its free edge in surface engagement with the lower crushing roll 12; in the preferred arrangement said free edge of the scraper tip 19 is provided with ribs or grooves adapted to accommodate and fit the ribs or grooves 14 of said roll 12. As shown in Figs. 1 and 6 the scraper tip 19 extends from the roll 12 at a downward inclination and forms an extension of a correspondingly inclined guide member 20 of non-magnetic material provided on its upper surface with a non-magnetic cover-plate 21 preferably made of an abrasion resisting material and fixed in place, for instance, by means of bolts 22 which may also serve, as shown, to fasten the scraper tip 19 to the guide member 20. The latter is carried by and forms part of a non-magnetic bar 23 recessed at its lower portion as indicated at 24 for the purpose to be more fully set forth hereinafter. As shown in Figs. 3 and 5 the non-magnetic bar 23 and its associated elements are supported in a yoke consisting of a base-plate 25 of magnetic material and end members 26, the latter being provided with trunnions 27 whereby the scraper tip 19, the non-magnetic guide member 20 and the elements associated therewith are pivotally mounted in suitable bearings 28 in the frame 10; the non-magnetic bar 23 may be fastened to the base-plate 25 by screws 29. In order to enable the scraper tip 19 to be properly adjusted with respect to the crushing roll 12, any suitable means may be provided as exemplified for instance by the levers 30 keyed to the ends of the trunnions 27, and turn-buckles 31 pivotally connected with the levers 30 and the frame 10 as shown in Fig. 1. The arrangement being described may further include a chute 32 conveniently supported in the frame 10 and sloping downwardly from a point near the magnetic separator to a point adjacent

the surface of one of the mill rolls 15 as illustrated in Fig. 1.

In the illustrated example, the magnetic separator includes pole shoes 33 extending outwardly and upwardly from an edge of the magnetic base-plate 25 at spaced intervals as shown in Figs. 3, 4, 5 and 7. In addition, specially designed magnetic cores 34 are provided and include upright lower sections *a*, upright upper sections *b*, and intermediate horizontal sections *c* as shown in Fig. 7. The lower sections *a* of the cores 34 are in engagement with the magnetic base-plate 25 to which they are secured by iron bolts 35 whereby said base-plate 25 and cores 34 are held in magnetic contact with each other; the upper sections *b* and the horizontal sections *c* of the cores 34 are cast into the inclined member 20 made of non-magnetic material such as for instance bronze, the arrangement being such that the free end faces of the sections *b* and *c* are inclined and lie substantially flush with the outer surface of the inclined guide member 20 in spaced relation to each other transversely of said member 20 as shown in Fig. 5. At points in registry with the end faces of the horizontal sections *c* of the cores 34, the member 20 is provided with angle plates 36 of magnetic material fitted into suitable recesses 21^a with which the non-magnetic cover-plate 21 is provided as shown in Fig. 4; the angle plates 36 are further fitted over the delivery edge of the guide member 20 in surface contact with the end faces of the core sections *c* and with the arrangement described are separated from each other by non-magnetic sections of the cover-plate 21. The construction furthermore is preferably such that the cores 34 are located in registry with the pole shoes 33 while the latter are positioned in spaced vertical registry with the magnetic angle plates 36, as illustrated in Figs. 3 and 5.

The magnetic separator also includes magnetic coils 37 located in the recessed portion 24 of the nonmagnetic bar 23 and surrounding the lower sections *a* of the cores 34 as shown in Figs. 3, 4 and 5. In the illustrated example the coils 37 are all wound in the same direction and are connected with a source of electricity in any conventional manner to reverse the direction of the electric current in alternate coils 37 so that the magnetic polarity is reversed in alternate cores 34; obviously the same result may be obtained in other ways as by winding alternate coils in opposite directions.

In practice when the apparatus is in operation and the coils 37 are electrically energized, the cores 34 will be magnetized, the arrangement being such that the sections *b* and *c* of each core will be of the same magnetic polarity while the section of base plate 25 under core section *a* of each core will be of opposite magnetic polarity; throughout the series, the magnetic polarity of the core sections *a*, *b* and *c*, in alternate cores 34 is reversed, so that the core sections *a*, *b* and *c* of one set of cores will respectively correspond with each other in polarity and the sections *a*, *b* and *c* of the intermediate or other set of cores will respectively correspond with each other in opposite polarity with regard to the core sections *a*, *b* and *c* respectively of the first set of cores. Similarly the polarity of each pole shoe 33 will be opposite to the polarity of the co-operating angle plate 36 with which it is in spaced vertical registry.

In the operation of the apparatus which has been selected for the purpose of illustrating and

describing the novel separator, the cane which previously has been subjected to the action of the customary revolving cane knives, is passed between the crushing rollers 11 and 12 from which the mat of crushed cane, after traveling over the magnetic separator, passes downwardly along the chute 32 to the mill rolls 15 and from thence through the remaining portions of the apparatus until the particular process has been completed. During these operations the magnetic coils 37 being electrically energized, part of the magnetic flux generated in the sections *a* of the cores 34 passes through the base-plate 25 to the pole shoes 33 thereof. As the polarity at the end of each coil is opposite, magnetic flux of opposite polarity coincidentally passes through the sections *b* and *c* of the cores 34 so that the angle plates 36 which are in metallic engagement with the sections *c* are correspondingly magnetized and accordingly are opposite in polarity to the polarity of the pole shoes 33 with which they are respectively in spaced vertical registry. As a result of this, magnetic fields are developed between each pole shoe 33 and the co-operating angle plate 36 in spaced vertical registry there-with, these magnetic fields being relatively powerful and being located outside and independent of the path of the travelling mat of cane or equivalent moving body of other material. The magnetic flux which continues upwardly through the sections *b* of the cores 34 radiates magnetic lines of force between adjacent cores, which as previously stated are of alternately reversed polarity in said sections *b*; with this arrangement open magnetic fields are thus created along the guide member 20 in the path of travel of the mat of cane or equivalent body of material and transversely to said path. Although the magnetic pull is strongest directly over the sections *b* of the cores 34, the holding strength of the magnetic fields is materially reduced by the intervening non-magnetic cover-plate 21 which has been provided for this purpose. As a result of this, any stray pieces of iron, steel or other substances contained in the mat of cane or equivalent material will merely be pulled downwardly through the mat and held in contact with the non-magnetic cover-plate 21; in other words, the resulting magnetic fields have a strength sufficient to draw any magnetizable substances contained in the traveling body of material to the surface of the cover-plate 21 but insufficient to prevent the movement of said substances with said traveling body along said guide member. By the action of the downwardly moving mat of cane or equivalent material as it passes from the crushing rolls to the first mill, the aforesaid stray pieces of iron, steel or other substances are accordingly carried downwardly toward the delivery edge of the guide member 20, it being understood that this result may be accomplished with relatively little power because of the reduction of the holding strength of the strong magnetic fields due to the presence of the non-magnetic cover-plate 21. The downward movement of the stray pieces of iron, steel or other substances over the non-magnetic cover-plate 21 is continued until the angle plates 36 are reached which angle plates as previously stated are strongly magnetized. Since strong magnetic fields are developed adjacent the delivery edge of the guide member between the angle plates 36 and the pole shoes 33, the stray pieces of iron, steel or other substances being pushed downwardly with the moving mat of cane or equiva-

lent material will finally be completely withdrawn from the traveling mat or other body of material and caused to bridge the magnetic gaps between said angle plates 36 and the pole shoes 5 33; the stray pieces accordingly will be strongly and firmly held at these points which are well outside of the path of the moving mat of cane or equivalent material. Such stray pieces of iron, steel or other substances which may accumulate 10 at the indicated points outside of the path of the mat of cane or equivalent material may be periodically removed in any convenient manner.

The scraper tip 19, the lower portion of which extends into close proximity to the upwardly extending sections b of the cores 34, if made of magnetic material becomes strongly magnetized by induction. While this arrangement may be desirable and preferred under certain conditions, it is not absolutely necessary in order to effect 20 the desired results. In other words, the scraper tip 19 may, if desired, be made of non-magnetic material in which case the magnetic flux expended in inducing magnetism in a scraper tip of magnetic material may be utilized to increase magnetic radiation or, in other words, to produce stronger magnetic fields over the non-magnetic cover-plate 21.

With the present arrangement when used in cane crushing apparatus as in the illustrated example, the magnetic separator may be placed directly adjacent to the crushing rolls so that the extraction of any stray pieces of iron, steel or other substances is commenced directly as soon as the crushed cane leaves the crushing 35 rolls 11 or 12 or their equivalent. Injury to the mill rolls by such stray pieces is accordingly guarded against and positively prevented.

The novel magnetic separator in all of its forms is of maximum efficiency in operation and 40 operates to first draw stray pieces of iron, steel or other substances towards the bottom of the traveling mat of cane or its equivalent and then definitely removes such stray pieces from the mat to a point outside of the path of travel 45 thereof, the extracted stray pieces of iron, steel or other substances being firmly and securely held outside of such path of travel until removed at convenient periodic intervals. The lower crushing roll may be magnetized in constructions where highly magnetized crushing rolls are in use and thus assist in the attraction of stray pieces of magnetizable material and the conduction thereof between the crusher rolls to customary tramp iron collectors, and the instant 50 arrangement may be effectively used in combination therewith; on the other hand the novel magnetic separator is equally well designed for efficient application to crushing rolls which due to their alloy composition become magnetized only to a negligible degree or not at all.

While the magnetic separator herein shown and described contains six coils or electro-magnets, it is to be understood that this number may be diminished or increased in dependence 55 upon the dimensions of the cane crushing or other apparatus and the thickness of the mat of sugar cane or equivalent material being treated therein.

Although the novel magnetic separator has 60 been illustrated and described as applied to a sugar cane mill, it is obvious as previously stated herein that it may be used in other types of machines and other installations in which the problem of separating magnetic substances from the 65 material being treated is presented.

Various changes in the specific forms shown and described may be made within the scope of the claims without departing from the spirit of the invention.

I claim:

1. A magnetic separator comprising a recessed non-magnetic supporting bar, an inclined non-magnetic guide member for a traveling body of material carried by said supporting bar, a magnetic base-plate secured to said bar, a non-magnetic cover-plate located in surface engagement with said guide-member and provided at intervals along its lower edge with recesses, magnetic angle pieces fitted over the lower edge of said guide-member and into the recess of said cover-plate; pole shoes on said base-plate at intervals in spaced vertical registry with said angle pieces, and electro-magnetic means mounted in said recessed supporting bar and including cores having upright upper and lower sections and transverse horizontal sections, the upper sections having their free end faces substantially in engagement with said non-magnetic cover-plate, the lower sections engaging said magnetic base-plate, and the horizontal sections engaging said magnetic angle pieces.

2. A magnetic separator comprising a recessed non-magnetic supporting bar, a non-magnetic guide member for a traveling body of material carried by said bar, a magnetic base-plate secured 30 to said bar, a plurality of magnetic cores each having sections of a given polarity terminating substantially flush with the surface of said guide member in spaced relation to each other, and each having another section of opposite polarity 35 in engagement with said base-plate, the polarity being reversed in alternate cores, electro-magnetic coils surrounding said cores for magnetizing the same, a non-magnetic cover-plate located on the surface of said guide member and provided with 40 spaced recesses adjacent the delivery edge of said guide member, magnetic angle plates fitted into the recesses of said cover-plate and over the delivery edge of said guide member in contact with sections of said cores, and pole shoes at spaced intervals on said base-plate in spaced vertical registry with said angle plates, each pole shoe and its co-operating angle plate being of opposite polarity whereby magnetic fields are created outside 45 of the path of travel of said body of traveling material for withdrawing magnetizable substances from said material and firmly holding the withdrawn substances outside of said path of travel of said body of material.

3. In a machine for crushing and treating sugar 55 cane including a pair of crushing rolls and a mill in spaced relation thereto, that improvement which comprises a magnetic separator consisting of a scraper tip in engagement with the lower crushing roll, a non-magnetic guide member carrying said scraper tip, the latter and said guide member extending in a downwardly inclined direction from said crushing roll toward said mill and together serving to direct the traveling mat of cane from said crushing rolls toward said mill, 60 a recessed non-magnetic supporting bar carrying said guide member, a magnetic base-plate secured to said bar, a plurality of magnetic cores arranged in spaced relation lengthwise of said bar and each having sections of a given polarity 65 terminating substantially flush with the surface of said guide member in transversely spaced relation to each other, and each having another section of opposite polarity in engagement with said base-plate, the polarity being reversed in alter- 75

- 5 nate cores, electro-magnetic coils surrounding said cores for magnetizing the same, a non-magnetic cover-plate located on the surface of said 10 guide member and covering corresponding sections of said cores whereby open magnetic fields are created along the surface of said guide member in the path of travel of said mat of cane and transversely thereto, said open magnetic fields having a strength sufficient to draw any magnetizable substances contained in the mat of cane to the surface of said cover-plate but insufficient to prevent the movement of said substances with said traveling mat of cane toward said mill, said cover-plate being provided with spaced recesses 15 adjacent the delivery edge of said guide member, magnetic angle pieces fitted into the recesses of

5 said cover-plate and over the delivery edge of said guide member in contact with sections of said cores, and pole shoes at spaced intervals on said base-plate in spaced vertical registry with said angle pieces, each pole shoe and co-operating angle piece being of opposite polarity whereby magnetic fields are created adjacent the delivery edge of said guide member and completely outside the path of travel of said mat of cane for completely withdrawing said magnetizable 10 substances from said mat of cane and firmly holding the withdrawn substances in fixed position outside of the continuing path of travel of said mat of cane toward said mill.

15

ERNEST GROSSENBACHER.
